RETRACTABLE AND EXTENDABLE TABLET ARM FOR A CHAIR

John Wilberforce Noel Jordan, Sheerness, Kent, England,
and James J. Chierchiaro, Easton, Pa., assignors to
JG Furniture Company, Inc., New York, N.Y., a cor-
poration of New York

Filed Oct. 28, 1966, Ser. No. 4,466

Term of patent 14 years

(Cl. D15—8)

FIG. 3.

FIG. 2.

FIG. 1.

FIG. 8.

FIG. 5.

FIG. 6

FIG. 7.

FIGURE 1 is a perspective view of a retractable and extendable tablet arm for a chair showing our design;

FIG. 2 is an enlarged elevational view of the tablet arm in extended position and disposed vertically;

FIG. 3 is an enlarged elevational view similar to FIG. 2 but shows the tablet arm fully extended to the right in horizontal position;

FIG. 4 is an enlarged elevational view showing the tablet arm in retracted position;

FIG. 5 is a top view looking down on the tablet arm as shown in FIG. 2;

FIG. 6 is a top view similar to FIG. 5 but shows the tablet arm in an extended horizontal position;

FIG. 7 is a front view of the tablet arm shown in FIG. 6;

FIG. 8 is a rear view of the tablet arm shown in FIG. 2;

FIG. 9 is a perspective view of the tablet arm fully extended to the right in horizontal position; and

FIG. 10 is a perspective view of the tablet arm in retracted position.

The dotted lines of FIG. 1 are for illustrative purposes only.

We claim:

The ornamental design for a retractable and extendable tablet arm for a chair, as shown and described.
